UNITED STATES PATENT OFFICE.

ARTHUR F. PITKIN, OF SCHENECTADY, NEW YORK.

SHEET CONNECTION FOR STEAM-BOILER STAY BOLTS.

Application filed May 23, 1922. Serial No. 563,009.

To all whom it may concern:

Be it known that I, ARTHUR F. PITKIN, a citizen of the United States, and resident of Schenectady, in the county of Schenectady and State of New York, have invented a certain new and useful Improvement in Sheet Connections for Steam-Boiler Stay Bolts, of which improvement the following is a specification.

10 My invention relates to stay bolts for steam boilers of the class or type known as "flexible," in which the stay bolt is articulated, at one or both of its ends, to a sheet or sheets of a steam boiler for the purpose 15 of imparting flexibility to the boiler sheets and connecting stay bolt for exempting them from bending strains under variations of temperature.

The object of my invention is to provide, 20 in a stay bolt structure which is articulated to one or both of two boiler sheets that are relatively inclined, means for articulating the stay bolt proper to one or both of said boiler sheets, which shall be of simple and 25 inexpensive construction and application; of the lightest weight, compatible with proper strength; and of minimum projection from the exterior of the boiler shell.

The improvement claimed is hereinafter 30 fully set forth:

In the accompanying drawing: Figure 1 is a view of a portion of one of the outside sheets of a steam boiler, illustrating an application of my invention; and, Fig. 2, a 35 longitudinal section through the same, on the line II—II of Fig. 1.

In the practice of my invention, referring descriptively to the specific embodiment thereof which is herein exemplified, in 40 which the stay bolt is articulated to the boiler at one of its ends only, I provide a plug, 2, which, in its original condition, is of frusto-conical form, with parallel ends, and of tubular section, as shown at the left 45 in the drawing, its shell being made sufficiently thick to safely resist the strain to which it will be subjected in service. A short neck, 2^b, is formed centrally on the inner end of the plug, 2, and a ball, 2^a, which 50 is in the form of a truncated sphere, is forged or machined on the end of the neck, which is further from the plug. The plug is fitted in an opening, of corresponding form, in an outer sheet, A, of the boiler, and 55 is secured therein in any suitable known manner, as by being welded thereto, with

the application of proper welding material, 7, or by being screwed thereinto. A central tell tale hole, 2^c, is formed in the bottom of the plug, extending through the neck, 2^b, to, 60 or nearly to, the ball.

The ball, 2^a, is articulated to the adjoining end of the stay bolt, 1, by fitting in a socket, 1^a, thereon, said socket being turned over on the ball, to provide a bearing therefor. The stay bolt may be either articulated to the inner sheet of the boiler, in a similar manner, or be connected thereto by screw threads and a riveted over end, as in 65 ordinary practice.

In installing the stay bolt structure, the ball and stay bolt having been first articulated as above specified, the plug, 2, is secured in the outer boiler sheet, A, as by being welded thereto or screwed thereinto. 70 The shell of the plug is then cut off by a gas torch or other suitable cutting instrument, so as to be made parallel, around its top, with the outer boiler sheet, A, projecting therefrom only so far as the surrounding welding material, 7, extends above the sheet, if the plug should be secured thereto by welding, irrespective of the angularity 75 of the outer sheet to the axial line of the plug.

Among the advantages of my invention, which will be recognized by those familiar with locomotive boiler construction, there may be noted the ability to reduce the projection of the end connecting member from 80 the outer boiler sheet to the lowest practicable degree; the resultant easy application of the lagging jacket, and brackets; material reduction in weight; and protection of the outer opening of the tell tale hole. 85

I claim as my invention and desire to secure by Letters Patent:

1. In a steam boiler stay bolt structure, the combination, with a steam boiler sheet, of an end connection member, for articulation to a stay bolt, said member having a tubular body, the top of which is parallel with the boiler sheet, in which it is adapted to be secured, and which is inclined relatively to its axial line. 100

2. In a steam boiler stay bolt structure, the combination, with a steam boiler sheet, of an end connection member, having a tubular body, the top of which is parallel with the boiler sheet, in which it is adapted to 105 be secured, and which is inclined relatively to its axial line, and a neck and ball pro-

- jecting from its inner end, for articulation to a stay bolt.
3. In a steam boiler stay bolt structure, the combination, with a steam boiler sheet, of an end connection member, having a tubular body, the top of which is parallel with the boiler sheet, in which it is adapted to be secured, and which is inclined relatively to its axial line, a neck and ball projecting from its inner end, for articulation to a stay bolt, and having a tell tale hole, extending through its bottom and neck.
4. The improvement in the manufacture

of a stay bolt structure, which consists in articulating an end connection member of 15 truncated cone form, to a stay bolt; securing said connection member in an outer boiler sheet which is inclined relatively to the axial line of the connection member; and thereafter cutting off the shell of said member to parallelism with the boiler sheet.

ARTHUR F. PITKIN.
